CLAIM

The ornamental design for a rack bracket, as shown and described.

DESCRIPTION

FIG. 1 is a front left perspective view of a rack bracket according to the present design.

FIG. 2 is a front right perspective view of FIG. 1.

FIG. 3 is a rear left perspective view of FIG. 1.

FIG. 4 is a rear right perspective view of FIG. 1.

FIG. 5 is a bottom view of FIG. 1; and,

FIG. 6 is side view of FIG. 1.

The rack bracket is shown with a symbolic break in its length. The appearance of any portion of the article between the zig-zag lines of the figures forms no part of the design.
